Inventor
NOAH D. ANDERSON

By *Richard B. Dorem*, Attorney

UNITED STATES PATENT OFFICE.

NOAH D. ANDERSON, OF BRAINERD, MINNESOTA.

RAZOR.

Application filed December 29, 1925. Serial No. 78,236.

This invention relates to improvements in razors and has particular reference to the type known as safety razors.

An important object of the invention is to provide a razor of the above character which may be placed in a firm and efficient shaving position, and at the same time permit movement of the blade to be brought in a convenient stropping position.

10 A further object of the invention is to provide a razor of the above type designed to improve generally upon the common forms of structures now in use, and whereby the blade may be quickly placed in association with the holder and readily removed for cleaning purposes.

A still further object of the invention is the provision of a safety razor of durable and comparatively simple construction arranged so as to be conveniently operated.

20 A still further object of the invention is the provision of a safety razor of durable design yet constructed so as to be sold at a comparatively low cost.

25 Other objects and advantages of the invention will become apparent as the description progresses.

In the accompanying drawing forming a part of this specification and in which like numerals are employed to designate corresponding parts throughout the same:

30 Figure 1 is a side elevational view of a razor constructed in accordance with my invention,

35 Figure 2 is a top plan view of the same, Figure 3 is a fragmentary vertical sectional view taken on the line 3—3 of Figure 2,

40 Figure 4 is a similar view taken on the line 4—4 of Figure 2,

Figure 5 is a transverse horizontal sectional view taken on the line 5—5 of Figure 1,

45 Figure 6 is a fragmentary perspective view of the retaining structure,

Figure 7 is a perspective view of a razor blade used in connection with my construction,

50 Figure 8 is a perspective view of a detail member forming a part of my structure, and

Figure 9 is a fragmentary side elevational view showing the blade arranged in stropping position.

55 In the drawing, wherein for the purpose of illustration is shown the preferred embodiment of my invention, the numeral 10

designates the handle of my improved razor structure, this handle being preferably in the form of a longitudinal tube open at its extremities. The lower end of the tubular handle 10 is provided with an outwardly flared portion 11 adapted to permit convenient connection of an interior member to be described more fully hereinafter. Formed integral with and secured in any suitable manner to the upper end of the handle 10 is a laterally extending guard plate 12 preferably disposed at a slightly downwardly inclined angular position and having its rear longitudinal edge curved slightly upward as 60 at 13. The forward longitudinal edge of the guard plate 12 is curved downwardly and has a plurality of transverse notches formed therein, providing a series of spaced arcuately formed teeth 14. The lateral 65 edges of the plate 12 are provided at the intermediate portions with oppositely disposed recesses 15, the purpose of which will become apparent as the description progresses.

70 Arranged so as to be snugly fitted in the tubular handle 10 and project substantially from the upper and lower portions thereof is a cylindrical interior sleeve 16 provided at its lower portion with a longitudinal slot 17 adapted to provide an expansible sleeve movable in the handle and at the same time fitting snugly therein. The upper end of the sleeve 16 is enclosed by an arcuate top plate 18 and the lower end is open. Formed adjacent the upper closed end of the sleeve on the side thereof is a rectangular shaped opening 19 provided at its upper edge with a reduced notch 20 designed to suitably engage a blade projection. In order that the 75 razor may be securely fastened to the sleeve 16, the upper extremity of the sleeve is provided with a pad 21 formed of metallic or similar material designed to conveniently permit engagement with an extension of the 80 razor blade.

85 In carrying out my improved razor construction, I contemplate the provision of a special form of razor blade, this blade embodying a substantially rectangular shaped blade body 22 tapered in cross section so that the forward edge will terminate in a sharp cutting edge 23 and the rear edge will be of rounded formation. Formed at the extremities of the rear rounded edge of the 90 blade 22 are end beads 24 of substantially semi-circular formation arranged to permit 95

secure mounting of the blade on the guard plate and prevent lateral displacement thereof. The lateral edges of the blade 22 are formed with arcuate recesses 25, designed to engage suitable retaining means to be described more fully hereinafter. With particular reference to Figure 7, it will be noted that the blade is formed with a rearwardly extending tongue 26 projecting from the central portion of the blade and substantially rectangular in cross section. This tongue is of tapered formation, expanding to provide an enlarged projecting head at its end.

15 In the shaving position, the razor blade 22 is arranged so as to be positioned horizontally upon the guard plate 12, the blade being designed to be snugly fitted on the guard plate so that the beaded ends 24 will be positioned against the lateral edges of the plate. The tongue 26 formed on the blade extends through the opening formed in the upper end of the sleeve 16 and the upper side of the tongue contacts with the pad 21 formed in the upper end of the sleeve. The tongue is tightly wedged in the sleeve, by the provision of a spring urged retaining member 27. This retaining member is of cylindrical formation arranged to be slidable in the sleeve 16 and is provided at its lower end with a bore 28 extending substantially into the central portion thereof. The interior of the retaining member 27 is provided with a central downwardly projecting pin 29 adapted to engage the upper end of a coiled compression spring 30. The lower end of the compression spring 30 is confined against downward movement by a transversely extending brace pin 31 adapted to engage the lower end of the spring, so that the spring will normally force the retaining member 27 against the upper end of the sleeve. When a blade is mounted in position on the razor, the tongue 26 is inserted through the opening and disposed between the pad 21 and the retaining member, and firmly held in position by the action of the spring 30.

50 In order that the body of the blade may be securely held in position on the guard plate 12 a pair of clamps 32 are pivotally mounted in the recesses formed in the lateral edges of the guard plate, the upper extremities of the clamps being provided with horizontally extending lugs 33 extending over the blade to prevent displacement thereof. The lower extremities of the clamps 32 are of arcuate formation designed to provide actuating plates.

60 Referring now to Figure 4 of the drawing, it will be noted that the lower side of the guard plate 12 is provided with a pair of downwardly projecting brackets 34 arranged in spaced relation to the lateral edges of the plate in alignment with the clamps. These brackets are designed to engage the inner

end of a pair of coiled compression springs 35 extending laterally from the brackets and having their outer extremities engageable with the intermediate portions of the clamps 32. From this construction, it is apparent that the springs 35 are secured to the clamps below the pivotal connection and therefore normally swing the lower extremities of the guard plates outwardly and the upper ends inwardly for securing the razor blade.

75 From the foregoing construction, it can be readily seen that the razor blade 22 will be firmly fastened in position upon the guard plate, so that the blade may be readily utilized for shaving purposes. The connecting means, on the other hand, are arranged so that the blade may be very quickly disconnected from the holder when desirable and means are also provided for utilizing the holding for stropping the blade.

80 This stropping operation is accomplished by withdrawing the interior sleeve 16 from the tubular handle 10 and placing the blade 22 at a right angular position relative to the normal shaving position. Thus the blade will be arranged in a position parallel to the length of the sleeve, as shown to advantage in Figure 9, so that the blade may be conveniently stropped.

85 It is therefore thought to be obvious, that a razor arranged to provide an efficient shaving apparatus, and adjustable to provide a stropping holder has been disclosed, embodying means for securely and detachably fastening a blade in a lateral angular position relative to the handle to facilitate the shaving operation, and also embodying structure adapted to permit stropping of the blade upon the conventional types of razor straps. It will be readily noted, that the blade fastening mechanism is of simple and durable design especially arranged to permit rapid connection of the blade, so that the change of the blade from a shaving to a stropping position requires very little time.

90 It is to be understood that the form of my invention herewith shown and described is to be taken as the preferred example of the same, and that various changes as to the shape, size and arrangement of parts may be resorted to without departing from the spirit of the invention or the scope of the subjoined claims.

95 With reference to Figure 6 it will be noted that the guard plate 12 is provided with a longitudinal groove 24' adjacent its rear, formed to snugly receive therein the bead 24 formed on the blade 22.

100 Having thus described my invention, I claim:

1. A razor comprising, in combination, a tubular handle, a guard plate formed adjacent the upper end of the handle extending laterally therefrom, a sleeve adapted to be mounted in the tubular handle, retaining

- means mounted adjacent the upper end of the sleeve, a blade having a projection formed on the rear edge thereof, means for securely fastening the blade body in position upon the guard plate, the projection being inserted in the sleeve and engaged by the retaining member, and means whereby the sleeve may be withdrawn from the handle to permit stropping of the blade.
- 10 2. A razor comprising, in combination, a tubular handle, a guard plate secured adjacent the upper end of the handle, a sleeve movably secured in the handle having an opening formed adjacent the upper end, a blade having a tapered tongue formed on the rear edge thereof, means provided on the guard plate for engaging the body of the blade, spring urged retaining means mounted in the sleeve for securely engaging the tongue of the blade, and means whereby the sleeve may be disconnected from the handle and the blade swung in a right angular position for convenient stropping thereof.
- 15 3. A razor comprising, in combination, a tubular handle, a guard plate secured adjacent the upper end of the handle and extending in an angular position therefrom, an expansible sleeve slidably mounted in the handle having an opening formed adjacent the upper end thereof, a spring urged retaining member formed at the upper end of the sleeve, a razor blade having a rectangular body portion and a tapered tongue extending from the rear edge, the said tongue being in engagement with the opening formed in the upper portion of the sleeve and firmly engaged by the retaining member mounted therein, clamps pivotally mounted on the guard plate engageable with the lateral edges of blade body, the blade being positioned in the sleeve so that the blade may be placed in a position parallel with the length of the sleeve and held in engagement with the sleeve for stropping.
- 20 4. A razor comprising, in combination, a tubular handle, a blade guard plate secured at the upper end of the handle and projecting laterally therefrom at an angular inclination, the rear edge of the guard plate being turned upwardly and the forward edge provided with downwardly curved teeth, a sleeve having a longitudinal slot slidably in the handle and provided with an opening adjacent the upper end, a blade having a rectangular tapered body and a tapered tongue projecting from the rear edge thereof, the body being engageable with the guard plate and retained in position by spring pressed clamps, the tongue being engageable with the opening formed adjacent the upper end of the sleeve, a spring pressed retaining member mounted adjacent the upper end of the sleeve engageable with the blade tongue for retaining same firmly in position, the opening in the sleeve being arranged to permit movement of the blade to a position parallel with the length of the sleeve and engagement by the spring pressed member to facilitate stropping of the blade.
- 25 5. A razor comprising in combination, a tubular handle, a guard plate secured to the upper end of the handle, a tubular sleeve slidably mounted in the handle and having an opening formed in its upper portion, a spring pressed blade holding member mounted in the upper portion of the sleeve, a blade, a rectangular shaped tongue formed on the rear edge of the blade engageable with the recess in the sleeve, the said tongue being adapted to engage the said spring pressed member to support the blade in transverse position on the holder or in axial position on the sleeve.
- 30 6. In a safety razor, the combination with a tubular handle having a guard plate secured at its upper end, an expansible tubular sleeve slidable within the tubular handle and a blade having a tongue, of means including a spring pressed blade holding member, having a noncircular transverse slot in its upper end adapted to engage the projecting tongue of the blade to rigidly support the same in a transverse position on the blade guard or in an axial position at the upper end of the sleeve.
- 35 7. In testimony whereof I affix my signature.
- 40 8. NOAH D. ANDERSON.
